UNITED STATES PATENT OFFICE.

AUGUST J. CARTER, OF CHATTANOOGA, TENNESSEE.

TUFTING-ATTACHMENT MECHANISM FOR SEWING MACHINES.

Application filed July 21, 1922. Serial No. 576,540.

To all whom it may concern:

Be it known that I, AUGUST J. CARTER, a citizen of the United States, residing at Chattanooga, in the county of Hamilton 5 and State of Tennessee, have invented new and useful Improvements in Tufting-Attachment Mechanism for Sewing Machines, of which the following is a specification.

This invention relates to improvements in 10 sewing machines, and particularly to mechanism forming an attachment to a sewing machine for making tufted work on sheeting or woven fabrics.

One of the objects of the invention is to 15 provide comparatively simple mechanism associated with a sewing machine to automatically form a series of loops in regular sequence in sheeting or fabric, and to sever the loops to form a long pile which is securely held intact with the sheeting or fabric, to withstand loosening or displacement during washing operations and also to increase the wearing durability of this class 20 of products.

25 A further object of the invention is to provide comparatively simple and effective means for tufting sheeting or woven fabrics to produce spreads which have heretofore usually been manually tufted, with material saving in the cost of production and selling price.

With these and other objects and advantages in view, the invention consists in the preferred construction and arrangement of 35 the several parts which will be more fully hereinafter described and claimed.

In the drawings:

Fig. 1 is a longitudinal vertical section on the line 1—1, Fig. 2, and showing the essential and well known structure of a sewing machine in side elevation;

Fig. 2 is a horizontal section on the line 2—2, Fig. 1;

Fig. 3 is a longitudinal vertical section 45 on an enlarged scale taken on the line 3—3, Fig. 4;

Fig. 4 is a transverse vertical section on an enlarged scale taken on the line 4—4, Fig. 1, and looking in the direction of the 50 arrow;

Fig. 5 is a detail perspective view of a part of the mechanism and particularly

showing the hook for forming the loop and the holding devices for said loop during the operation of the needle;

55

Fig. 6 is a transverse vertical section on an enlarged scale on the line 6—6, Fig. 2;

Fig. 7 is a transverse vertical section on the line 7—7, Fig. 2;

Fig. 8 is a plan view on an enlarged scale 60 of the hook and thread or strand holding mechanism and the operative devices therefor, the parts being illustrated both in full and dotted lines;

Figs. 9, 10 and 11 are transverse vertical sections taken a short distance inside of the needle and looking outwardly to illustrate the operation of the needle and the formation of the loops and the severance of the latter to produce the pile;

65

Figs. 12 and 13 are plan views on enlarged scales of portions of the throat plate together with the hook and means for holding and shifting the thread or strand during the operation of the needle, the holding 70 means for the thread or strand being illustrated in full and dotted lines;

70

Fig. 14 is a longitudinal section through a piece of sheeting or fabric showing the manner of securing the loops therein;

80

Fig. 15 is a section through a piece of sheeting or fabric taken in a plane at right angles to that shown by Fig. 14 and illustrating the appearance of the tufting when completed; and

85

Fig. 16 is a plan view of a piece of sheeting or fabric showing the appearance of the completed tufting.

The improved mechanism embodying the features of the invention is shown applied to a well known form of sewing machine comprising the usual supporting base or bed 5, an upwardly and outwardly projecting fixed arm or goose-neck 6 having a head 7, a main shaft 8 extending longitudinally over the bed through the lower portion of the arm 6, a driving pulley 9 on the said shaft, an eccentric 10 also mounted on the shaft near the driving pulley 9 and having a connecting rod 11 attached to a rocker arm 12 fulcrumed on one side of the fixed arm or goose-neck 6, as at 13, and having other end clamped or otherwise secured to a needle bar 14 reciprocatingly mounted in the head 7

90

95

100

and, as usual, provided with a removable needle 15 in the lower end thereof. The sewing machine mechanism also embodies a presser foot bar 16 provided with the usual means for raising and lowering the same and having a presser foot 17 of special form fixed to the lower end thereof to cooperate with a throat plate 18 slidably and removably mounted in a work support 19, which also serves to cover the mechanism. In Fig. 1 the work support and throat plate have been omitted, but are shown in Figs. 3 and 4, 9, 10 and 11. The sewing mechanism also includes a feed arm 20, as shown by Fig. 2, said latter arm being mounted to have a rocking and forward and backward movement through the medium of a rocking support 21 having a connection 22 to a crank means 23 on the forward end of the main drive shaft 8. The feed arm 20 carries two serrated feeders 24 disposed under and working through the throat plate as usual, the said feeders 24 being parallel and separated by a channel or throat 25. It will be understood from the foregoing that the feeders 24 have four motions imparted thereto to regularly cooperate with the work on the support 19 to progress the latter in accordance with the operation of feed devices of this class. The sewing machine mechanism is also provided with suitable tension means 26, as shown by Fig. 1, for the thread or strand 27 which is passed through a suitable loop 28 at the upper end of the needle bar 14 and then downwardly through the eye of the needle 15. The mechanisms thus far described, except the specific form of the presser foot 17, which will be hereinafter more fully explained, do not involve the features of the invention and the improved attachment mechanism is shown applied to the several sewing machine mechanisms specified to illustrate one practical application of the improvements. It will be understood, however, that the improved attachment mechanism may be applied to other sewing machine mechanism having essential parts similar to those described, and the operation of the improved attachment is effected from the main or drive shaft 8 and is carried on a supplemental base 29 secured to or formed as an integral part of and projecting outwardly from the sewing machine base 5.

On the main or drive shaft 8 a bevel gear 30 is secured and located adjacent to the lower end of the arm or goose-neck 6 and is in continual mesh with a similar bevel gear 31 fixed on the inner end of a short counter shaft 32 held in an upwardly projecting bearing 33 rising from the supplemental base 29 and a portion of the sewing machine base 5. On the outer end of the counter shaft 32 a bevel gear 34 is fixed and is of the same dimensions as the bevel gears 30 and 31, the shaft 32 being held against shifting movement in the bearing 33 by space collars 35 secured on said shaft between parts of the bearing as shown by Fig. 1. Over the front or outer portion of the supplemental base 29 a longitudinally disposed motion transmitting shaft 36 is mounted in suitable bearing posts or uprights 37, and on the right end of the said shaft 36 a bevel gear 38 is secured and held in continual mesh with the gear 34. Between the bearing posts or uprights 37 a bevel gear 39 is carried on the shaft 36, and on the left end of this shaft a similar bevel gear 40 is fixed and continually meshes with a bevel gear 41 on the outer end of a counter shaft 42 also held against movement in a bearing 43 rising from the supplemental base 29 by space collars 44. Between the upright bearings 33 and 43 is a similar bearing 45 supported by the supplemental base 29 and a portion of the sewing machine base 5, and mounted in this bearing 45 is a further counter shaft 46 having on the outer end thereof a bevel gear 47 held in continual mesh with the gear 39 and secured against shifting movement by space collars 48 mounted between parts of the bearing 45. On the inner or rear end of the shaft 42 is a crank 49, and on the inner or rear end of the shaft 46 is a similar crank 50, the two cranks 49 and 50 having a like position on the inner or rear ends of their shafts to provide for a similar operation thereof in connection with mechanism which will be hereinafter explained. Between the shafts 42 and 46 at a distance outwardly from and in line with the feed arm 20 and feeders 24 thereof is an angular bearing bracket 51 having an angular rocker arm 52 mounted in the inner upright member 53, the angular bearing bracket 51 being secured to the supplemental base 29. This rocker arm 52 has the requisite motions imparted thereto by a connecting rod 54 movably attached thereto and also to the lower end of the rocker arm 12 which controls the operation of the needle bar 14.

On the shaft 8 is an eccentrically mounted disk 55 which serves as a cam to impart a rocking movement to a yoke 56 having its bifurcation 57 formed with parallel side walls, this yoke 56 being secured to a slide rod 58 mounted in bearing uprights 59 and 60 rising from the sewing machine base 5 close to the shaft 8. This side rod on its right end has a transversely projecting pin 61 which continually bears on a face cam 62 also fixed to the shaft 8 at a suitable distance from the eccentrically mounted disk or cam 55. The face cam 62 is formed with a low part 63 and a high part 64 for imparting a reciprocating movement or a drawing action to the right on the said rod 58 when the pin 61 engages the high part 64 of the cam 62. The rod 58 is normally

pulled to the left through the action of a spring 65 secured to the yoke 56 and to a portion 66 of the bearing for the shaft 8 located adjacent to the rocking feed arm 20. The rod 58 is given a rather short reciprocating movement and after the pin 61 has passed from the high part 64 to the low part 63 of the cam 62, the spring 65 is free to exert its pulling tension on the rod 58 through the yoke 56. The yoke 56 and the eccentrically mounted disk or cam 55 have such relative proportions that the reciprocating movement of the rod 58 may ensue without disengagement of the yoke 56 relatively to the disk or cam 55. The pin 61 is removably mounted in a head 67 at the right end of the rod 58 and may be replaced in the event that it wears down and loses its operating efficiency. The end 20 of the reciprocating rod 58 opposite that carrying the pin 61 is provided with an upwardly and forwardly extending loop retainer or arm 68, which has the function of disposing the loop of the thread or strand at regular intervals out of the path of the needle and to hold the said loop during other operations incident to the formation of a tuft. The loop retainer or arm 68 contacts with a fixed abutment or stop 69 extending in a direction reverse to the said retainer or arm 68 and consisting of an upwardly curved member secured at its outer end on an upright or post 70 rising from the supplemental bed 29 adjacent to the outer counter shaft 42. The inner free end 71 of the abutment or stop 69 is straight and presents a longer edge surface than the adjacent free end of the retainer or arm 68. The inner free end of the abutment or stop 69 is located close to the path of movement of the needle 15 and the free end of the loop retainer or arm 68 during its movement works close to the needle and during a certain period of its operation the end of the loop retainer or arm 68 has close engagement or contact with the inner end of the abutment or stop 69. The outer free end of the loop retainer or arm 68 is roughened or slightly serrated, as at 72, as clearly shown by Figs. 12 and 13, and the object of this roughened or serrated construction is to cause the end of the loop retainer or arm 68 to firmly engage the thread or strand and shift the latter to facilitate forming and getting a loop during the operation of the needle. The loop retainer or arm 68 is given a lateral swinging motion by the eccentric disk or cam 55 and a reciprocating movement by the high part 64 of the cam 62, the latter cam first moving the rod 58 and the loop retainer or arm 68 against the forward portion of the end edge of the abutment or stop 69, and then said rod and loop retainer or arm are rocked by the eccentrically mounted disk or cam 55 through the medium of the yoke 56 in a slightly arcuate plane towards the rear portion of the end edge of the abutment or stop 69, the loop retainer or arm 68 and the rod 58 under such operation being held in engagement with the inner free end of the stop or abutment 69 by the spring 65, in view of the fact that at such time, or during the rocking movement of the loop retainer or arm 68, the pin 61 is in engagement with the low part 63 of the cam 62.

A hook 73 is carried by the rocker arm 52, as clearly shown by Fig. 5, the said hook comprising a body 74 having a stud 75 secured in a head 76 forming part of the rocker arm and to which the connecting rod 54 is attached. The rear portion of the hook 74 is in the form of a hook bill 77 which is longer than the body 74 and is provided by bifurcating the body as at 78, 80 the said hook bill 77 being tapered to form a reduced free end 79. Extending through one end of the body 74 and partially through the length of the hook bill 77 is a slot 80 which is formed entirely through the bottom portion of the body and bill. By bifurcating the body 74 of the looping means comprising the hook bill 77, an opening for the clearance and descent of the needle 15 is provided and the said looping means is by this construction also permitted to be mounted close to the path of reciprocation of the needle 15 to effectively operate in conjunction with the thread or strand when the needle has descended a certain distance below the throat plate. It will be observed that the needle bar 14 and the rocker arm 52 carrying the looping means are connected to the same intermediate actuating device, or the rocker arm 12 employed in this type of sewing machine, to impart a regular reciprocation to the needle bar, and hence the needle bar, needle and looping means comprising the hook bill 77 will have a timed operation to effectively form a loop during each descent of the needle and needle bar.

A knife carrier is connected to and operated by the cranks 49 and 50 secured to the inner ends of the counter shafts 42 and 46, 115 the said carrier consisting of a flat bar 81 having a bifurcated end 82 for sliding engagement with the crank 49 and the opposite end pivotally fixed to the crank 50. As clearly shown by Fig. 3, a knife or cutter 83 is adjustably secured on the outer side of the carrier or bar 81 and is disposed at an upward and outward angle of inclination, said cutter or knife being held in fixed position yet readily adjustable to modify the angle of the same if desired by a set screw 84 engaging a longitudinal slot 85 formed in the center of the cutter or knife. By the formation of this longitudinal slot 85, the cutter or knife 82 may also be adjusted length-

wise of the carrier or bar 81, and it is preferred that the upper and lower edges 86 and 87 of the cutter or knife be sharpened so that the said latter device may be reversed to bring each cutting edge uppermost. By disposing the cutter or knife 83 on the carrier or bar 81, at an angle as specified, and projecting a portion of said cutter above the upper edge of the carrier or bar, a draw-cut operation ensues when the carrier or bar 81 is reciprocated, and the said cutter or knife is given a proper elevation to render it effective in severing the loops of the thread or strand as produced by the looping mechanism, the cutter or knife moving upwardly into the slot 80 a sufficient distance to accurately cut all of the loops while the latter are held taut. By the rocking movement of the looping means the successive loops are caused to ride over the hook bill 77 in positions for positive severance by the cutter or knife 83 as the latter moves upwardly into the slot 80. After the cutter or knife 83 has performed its function, it recedes or is lowered relatively to the looping means, or passes out of the slot 80 of said latter means by the cranks 49 and 50 engaging the opposite ends of the carrier or bar 81. By bifurcating the one end of the carrier or bar 81, binding or jamming of the said carrier or bar is prevented and an easy and regular movement thereof ensues.

The presser foot 17 differs from the ordinary sewing machine presser foot to accommodate the bulk of the work passing thereunder over the throat plate 18. In the present instance the throat plate 17 is comparatively elongated and has the opposite ends 88 turned upwardly, as clearly shown by Fig. 4, and in the front extremity of this plate at the base of the front upwardly turned angular end 88 a needle opening 89 is formed as usual in devices of this character. The rear part of the presser foot 17 also has a bottom groove 17^a adapted to be located over and cooperate with the channel or groove 90 in the throat plate 18, to clear the loops and prevent any tendency to a jam under the rear part of the said foot. The elongation of the presser foot 17 provides for positive retention of the work over the throat plate 18 and feeders 24 during the formation of the loops and completion of the tufts and to insure a close guidance of the work over the throat plate and movement of the cut loops through an upwardly and rearwardly inclined channel 90 formed in the centre of the throat plate or between slots 91 through which the feeders 24 have movement. The channel 90 starts at its lowermost point at the rear terminal of an opening 92, which permits the cut loops or finished tufts to pass upwardly through the throat plate and into the channel, as shown by Fig. 11, where it will be observed that the

presser foot 17 holds the fabric closely down on the work support 19, and the channel 90 gives the necessary clearance for the cut loops or finished tufts without liability of choking. It will be understood that the throat plate 18 will be mounted and secured in the work support 19 in such a manner that it may be removed when found necessary, and furthermore the presser foot 17 may be readily detached from the presser bar 16.

The working face of the cam 62 is preferably constantly lubricated by an absorbent medium 93 supported adjacent to the rear portion of the cam as shown by Figures 6 and 8, and by this means the pin 61 and cam 62 will have an easy cooperation with reduced friction and wear on the respective parts. It will also be understood that lubricating means will be provided at other points for maintaining the several operating instrumentalities in good running order.

In preparation for operation the thread or cord supply is carried on a large spool or reel mounted in convenient position for feeding to the mechanism, the said thread or cord being first passed through the tension means 26 and then through the feeding loop 28 at the upper end of the needle bar 14 and then downwardly through the eye of the needle 15. The work or fabric is placed on the work support 19 over the throat plate 18 and held in close contact with the latter by the presser foot 17 which is lowered as usual. At the beginning of the operation, the needle 15 is elevated to the uppermost limit of its stroke, the loop forming means comprising the body 73 and hook bill 77 is over to the left at the outward limit of its stroke and the loop retainer or arm 68 has its free end spaced from the inner free end of the abutment or stop 69, and the carrier 81 is at the upper limit of its stroke or highest point with the knife or cutter 83 in the slot 80. The needle with the thread strand or cord descends through the opening 89 of the presser foot 17 and immediately the looping means including the hook bill 77 begins to move over toward the right and the loop retainer or arm 68 moves laterally in a rearward direction to clear the needle which passes downwardly close to the inner free end of the abutment or stop 69. The loop forming means including the hook bill 77 continues to turn to the right until the reduced end of said bill is in line with the rear portion of the needle 15 and the loop retainer or arm 68 also continues to move laterally in a rearward direction adjacent to the rear portion of the inner free edge of the abutment or stop 69. When the needle 15 has fully descended or reached the lower limit of its stroke, the loop forming means including the hook bill 77 promptly starts to move to the left

or in an outward direction, and the reduced free end of the said hook bill passes between the rear portion of the needle and the thread, strand or cord and at this time the loop retainer or arm 68 moves back or to the right and swings over to the front to give the needle free clearance in its upward movement through the fabric. During the movements of the parts just specified the carrier 81 having the knife or cutter 83 thereon are then regularly moving upwardly, and just as the loop forming means including the hook bill 77 has reached the limit of its outer stroke the knife or cutter 15 will enter the slot 80 and sever the loop while the thread strand, or cord is held above, and at the same time the thread, strand or cord will be engaged by the free end of the loop retainer or arm 68 and 20 pressed against the inner end of the abutment or stop 69, the thread, strand or cord also being held above by the presser foot 17. The position of the parts during the several steps of movement just explained 25 is clearly illustrated by Figs. 9, 10 and 11, the full throw of the loop forming means including the hook bill 77 to the right being shown by Fig. 9, and the castover and cutting of the loop being illustrated by Fig. 10, and the completion of each loop or tuft and 30 the return of the needle to its uppermost stroke limit being clearly shown by Fig. 11. The movement of the loop retainer or arm 68 relatively to the inner end of the abutment or stop 69 is also shown in full and 35 dotted lines by Figures 12 and 13 together with the relative position of the loop forming means including the hook bill 77. When each loop has been severed or its 40 formation completed and passes rearward in the form of part of the tufting shown by Figure 11, the same operation is effected and the successive loops as formed by the descent of the needle and engagement of the 45 hook bill 77 of loop retainer or arm 68 will be repeated in regular sequence. As shown by Figure 14 it will be seen that the loops through the fabric as at "A" will be in part held in the same opening formed by the 50 penetration of the needle through the fabric B, or there will be a part of each loop extended through one of the openings "a" and whereby portions of two loops will 55 occupy the same opening and thus set up a tight frictional binding and a stronger and more durable tension of the loops in the fabric, this operation being similar to ordinary stitching with an advantageous result in the finished product. As hereinbefore explained the completed cut loops or tuft members are drawn rearwardly with the fabric B and the free extremities thereof 60 are pulled upwardly through the opening 92 in the throat plate and then rearwardly 65 through the channel 90, as shown by Fig. 11,

and in part under and through the groove 17^a of the presser foot 17. After the fabric B has been subjected to the formation of the loops or tuft members therein, the free ends of the secured and cut loops will present 70 a fluffy appearance, as at C, as shown by Figs. 15 and 16.

The spreads for beds and other analogous use which are subjected to the action of the improved mechanism for tufting operation are usually formed of unbleached domestic material, and when laundered this material will shrink considerably, thereby closing the components of the fabric tight around the tufts. The free parts of the loops or the pile ends, which are formed by cutting the loops, frazzle or fluff and are prevented from working out of the fabric, and the more the latter is washed the tighter the tufts will be held. The complete spread 80 subjected to the tufting operation or action of the mechanism hereinbefore explained will also stand washing by hand or mechanical laundry apparatus in any manner. 85

The loop forming or tufting operation above described is expeditiously carried on and various designs may be worked out in accordance with a pattern that may be outlined on the fabric, and as hereinbefore indicated, the improved mechanism is particularly adapted for tufting spreads. The mechanism, however, is also intended to be used in forming cut loops or tufts on other fabrics. 90

It will be seen that a single needle 15 serves as the main element for assisting in forming the successive loops, and as hereinbefore stated, the improved attachment mechanism is applied to and operates with the essential components of a sewing machine of a commercially well known form. The loops before successive severance are held taut around the bill hook 77 and are shifted over the latter so that parts of the loops cross the bottom portion of the slot 80 which extends longitudinally of the center of a part of said hook, and as a consequence all of the loops are evenly cut and the tuft pile is thereby given an even length throughout the whole tuft formation. 105 110 115

What is claimed as new is:

1. In a machine of the class specified, the combination with a reciprocating needle, means for guiding a strand thereto, loop forming mechanism, and cutting means separate and apart from the loop forming mechanism and mounted to have a rising and falling and reciprocating movement independently of the movement of the loop forming mechanism for severing the loops to produce closely associated pile members of equal length. 120 125

2. In a machine of the class specified, the combination with a reciprocating needle and means for guiding a strand thereto, means 130

- for holding a fabric for penetration by the needle and strand, loop forming mechanism, and cutting means having a mounting separate from the loop forming mechanism and 5 actuated to have a rising and falling and reciprocating movement into engagement with and away from the loop forming mechanism for severing the loops to form closely associated successive pile members of equal 10 length.
3. In a machine of the class specified, means for holding a fabric, a reciprocating needle and means for guiding a strand to the needle, the needle and strand operating to 15 penetrate the fabric, loop forming and holding mechanism cooperating with the needle, and cutting means mounted separately with relation to the loop forming and holding mechanism and having a rising and falling 20 and reciprocating movement independent of the operation of the loop forming and holding mechanism and movable into and from the rear portion of the said latter mechanism for equally severing the loops held by 25 the loop forming mechanism.
4. In a machine of the class specified, mechanism for penetrating and securing a loop in stitch-like form in a fabric, means for forming successive loops in the fabric, 30 means for separating and holding parts of the individual loops, and cutting means mounted separately with relation to the means for separating and holding parts of the loops and having a rising, falling and 35 reciprocating movement in and through a portion of the means for separating and holding parts of the loops for regularly and equally severing the loops to form pile members of equal length relatively to one side 40 of the fabric.
5. In a machine of the class specified, a device for penetrating a fabric and carrying a strand which is passed through the fabric by said device, means for forming the 45 strand into successive loops and tautly holding the latter at intervals, and cutting means mounted separately with relation to the means for forming the strand into successive loops and holding the latter, the said cutting means having a swinging movement 50 into and away from a portion of the said loop forming and holding means to form closely associated pile members of equal length on one side of the fabric.
6. In a machine of the class specified, means for carrying a strand for penetrating a fabric and passing the strand through the latter, loop forming means having an oscillating movement and cooperating with the 55 strand carrying means to produce successive loops below the underside of the fabric, and cutting means having a separate mounting relatively to the loop forming means and actuated to move upwardly towards and into 60 and through a portion of the loop forming means for regularly and equally severing the successive loops to form closely associated pile members of equal length in the lower side of the fabric.
7. A sewing machine having the usual reciprocating needle and means for supplying a strand thereto, and separately mounted and independently movable means for respectively forming and holding successive loops in taut condition and regularly and 70 equally severing the loops as formed, the severing means being movable into and through a portion of the means for forming and holding the loops and entirely clearing the latter means at intervals.
8. A sewing machine including a single reciprocating needle and means for guiding a strand thereto, means for forming a loop at one side of the needle and holding the loop taut after its formation, and cutting means separately mounted with relation to the loop forming means and having a swinging movement towards and into a portion of the loop forming means for equally cutting the loop to form pile members of equal 75 length.
9. A sewing machine having the usual single reciprocating needle and means for guiding a strand thereto, loop forming means having a swinging movement to and from the needle to form successive loops when the needle descends and provided with a member to hold the loops in taut condition, and cutting means mounted separately with relation to the loop forming means and having an angularly disposed cutter with a cutting side edge to enter and pass through a portion of the loop forming means for equally cutting the loops while the latter are held in 80 taut condition.
10. A sewing machine having the usual needle and means for guiding a strand to the latter, a stop abutment and loop retaining means cooperating therewith to shift each loop laterally, loop forming means, and means for equally cutting the successive loops as formed, the loop forming and cutting means being mounted separately from and movable independently of each other 85 and the loop retaining means.
11. A sewing machine having the usual reciprocating needle and means for guiding a strand thereto, loop forming means mounted to swing with relation to the needle and comprising a bill hook to engage the strand when the needle is in its lowermost position, laterally movable means for holding the individual loops in taut condition, and cutting means mounted separately from 90 and below the loop forming means and movable upwardly into a portion of said loop forming means for regularly and equally severing the loops as formed.
12. A sewing machine having the usual reciprocating needle and means for guiding 95

- a strand thereto, rocking hook means cooperating with the needle when the latter is in its lowermost position to form loops, and a cutter mounted below and separate from the
- 5 rocking hook means and regularly movable upwardly into a portion of the said hook means to equally sever the successive loops.
13. In a machine of the class specified, a single vertically reciprocating needle provided with means for guiding a strand thereto, an oscillating hook to engage a portion of the strand to form a loop, a fixed abutment, an oscillating loop retainer having a free end cooperating with the fixed abutment to hold and shift a portion of the strand relatively to the abutment, and means for cutting the loop while the latter is held taut, the loop retainer and cutting means being separated from and operable independently of the oscillating hook.
14. In a machine of the class specified, a single vertically reciprocating needle with means for guiding a strand thereto, means for drawing a portion of the strand away from the needle while the latter is in its lowermost position to form a loop, means for retaining the loop in taut condition, and means for cutting the loop while held in taut condition, the loop retaining and cutting means being separately mounted from and movable independently of the means for drawing a portion of the strand away from the needle.
15. In a machine of the class specified, a single vertically reciprocating needle provided with means for guiding a strand thereto, mechanism for successively drawing a portion of the strand away from the needle while the latter is in its lowered position, to form a loop, holding the separated portion of the strand taut while the needle is ascending, and cutting the loop to form pile members of equal length, the mechanism for drawing a portion of the strand away from the needle, holding the separated portion of the strand taut and for cutting the loop being separately mounted and having movements independently one with relation to the other.
16. In a machine of the class specified, a work support on which fabric is placed, a single vertically reciprocating needle provided with means for guiding a strand thereto, the needle operating to pass through the fabric and carry the strand therewith, means for separating a portion of the strand from the needle below the fabric to form a loop, means for holding the loop as the needle ascends, and means for equally cutting the loop while the latter is held in taut condition for forming closely associated pile members of equal length below and secured to the fabric, the means for separating the strand from the needle, for holding the loop as the needle ascends and for equally cutting the loop while the latter is held in taut condition being separately mounted devices having timed movements one with relation to the other.
17. In a machine of the class specified, a single vertically reciprocating needle provided with means for guiding a strand thereto, a work support upon which a fabric is adapted to be placed for passage of the needle and the strand therethrough, a movable device mounted to pass between the needle and a portion of the strand to form a loop and effect a sliding movement of the separated part of the strand over said device as the needle elevates, means for holding the separated part of the strand and shifting the latter out of the path of movement of the needle, and means for cutting the loop to form pile members of equal length, the said movable device, means for holding the separated part of the strand and shifting the latter, and means for cutting the loop being independently mounted and having timed sequential operations.
18. In a machine of the class specified, a work support having feeding means movable through a portion thereof to engage a fabric placed on the support, a single vertically reciprocating needle movable through the support relatively to the feeding means and provided with devices for guiding a strand thereto, a reciprocating hook movable between the needle and a portion of the strand for separating the latter from the needle to form a loop, means mounted independent of the hook for retaining the loop in taut condition, and means mounted independent of the said hook and loop retaining means for cutting the loop to form pile members of equal length.
19. In a machine of the class specified, a single vertically reciprocating strand-carrying needle, a work support adapted to have fabric placed thereon for penetration by the needle and strand, loop forming and holding means mounted below the work support to have a swinging movement towards the latter in the arc of a circle and holding the loop for an interval in taut condition, and cutting means mounted below and separate from the loop forming means and movable into and through a portion of and away from the loop forming means at intervals to form closely associated elongated pile members of equal length.
20. In a machine of the class specified, a work support adapted to receive a fabric thereon, a single vertically reciprocating strand carrying needle movable through the work support and fabric, a fixed stop means and a longitudinally reciprocating laterally oscillating loop retainer arranged below the work support in opposition and between the ends of which the needle has movement, an oscillating hook below the plane of the fixed

stop means and retainer and operating to separate a portion of the strand from the needle to form a loop which is held taut by the retainer against the stop means mounted 5 separately from and movable independently of the loop retainer and oscillating hook, and cutting means for severing the loop while the latter is held taut.

21. In a machine of the class specified, a 10 work support, a single vertically reciprocating strand carrying needle, a fixed stop having an inner free end, a longitudinally reciprocating and lateral oscillating loop retainer having a free end disposed opposite 15 the free end of the stop, an oscillating loop forming means including a hook bill below the stop and retainer for separating a part of the strand from the needle and holding the separated strand in the form of a 20 loop while the needle ascends, the hook bill being slotted for a portion of its length, and vertically reciprocating cutter mounted and operating independently of the oscillating loop forming means and movable into the 25 slot of the hook bill for severing the loop while the latter is held taut by the retainer against the stop.

22. In a machine of the class specified, a 30 work support for holding a fabric, a throat plate mounted in the work support, feeding devices for the fabric movable through the throat plate, the throat plate having an opening therethrough with a rearwardly and upwardly inclined channel leading 35 therethrough, a presser foot to engage the fabric on the work support having a groove in its lower side over the channel of the throat plate, a single vertically reciprocating needle provided with means for guiding a strand thereto, the needle being movable through 40 the presser foot and throat plate and the fabric, loop forming means below the throat plate, the loop forming means having a swinging movement close to the underside of 45 the work support, a loop holding means mounted separate from and operable independently of the loop forming means, and loop cutting means also mounted separately below and clear of the loop forming means 50 and movable into a portion of the latter at intervals to form pile members of uniform length, the pile members being successively drawn upwardly through the opening in the throat plate and through the channel of the 55 latter and groove of the presser foot by the feeding movement of the fabric.

23. A sewing machine comprising a work support and throat plate with feed devices working therethrough and adapted to hold a fabric, a single vertically reciprocating strand carrying needle, an elongated presser foot, the throat plate having a rearwardly and upwardly inclined channel leading therethrough and the presser foot provided with a longitudinal groove over the channel,

and mechanism connected to and operated by the main actuating mechanism of the sewing machine and including means for forming successive loops and severing the latter to produce a pile on the lower side of 70 the fabric of equal length, the loops being successively secured in the fabric by the needle and drawn rearwardly through the channel of the throat plate and groove of the presser foot as the fabric is moved over 75 the work support and throat plate.

24. A sewing machine having a work supporting means to receive a fabric, a feed mechanism for moving the fabric over the work support, a throat plate mounted in 80 the work support having an opening therethrough and an upwardly inclined channel leading therethrough and closed at its lower portion and opening through the top of the said throat plate, a single vertically reciprocating needle provided with means for guiding a strand thereto, an elongated presser foot having a groove in the lower portion thereof which registers with a portion of the opening through the throat plate 85 and the channel of the latter, and mechanism below and close to the work support for successively forming and securing loops in the fabric on the support and also for cutting the loops on the underside of the 90 fabric, the loop forming and cutting mechanisms being separately mounted and independently operable so that the cutting mechanism will entirely clear the loop forming mechanism at intervals, the fabric in 95 moving over the work support drawing the successive loops as formed out of the plane of operation of the said loop forming mechanism and through the opening and channel 100 of the throat plate and groove of the presser foot.

25. In a machine of the class specified, the combination of a sewing machine including a work support, a single vertically reciprocating needle provided with means for supplying a strand thereto, a throat plate in the work support having an opening therethrough and an upwardly and rearwardly inclined channel closed at its lower portion and opening through the top of the throat plate, an elongated presser foot disposed over and vertically movable to and from the throat plate and having a groove in its lower portion extending longitudinally thereof for registration with the opening and channel of the throat plate, feed means working through the throat plate on opposite sides of the opening and channel in the latter, and loop forming and cutting mechanisms disposed below the work support and held in separated relation and also provided with means for differently operating them and whereby the cutting mechanism which is normally clear of the loop forming mechanism will move into and through 110 115 120 125 130

a part of the latter mechanism to regularly sever the loops held by the loop forming mechanism.

26. The combination with a sewing machine having a single vertically reciprocating needle and work support and feed accessories, of a presser foot with an opening therethrough for movement of the needle and a groove extending longitudinally rearwardly from the said opening, a throat plate having an opening therethrough from the needle and continued rearwardly from the latter opening in the form of a slot which continues into a rear channel having a closed bottom portion, the bottom of the channel being rearwardly and upwardly inclined, the groove of the presser foot when the latter is down being disposed over the slot and channel of the throat plate, and separately mounted and independently movable loop forming and cutting mechanism disposed below the work support and throat plate and operated by the main actuating mechanism of the sewing machine, the loops as formed being drawn upwardly through the slot and channel of the throat plate and the groove of the presser foot as the work is fed over the support and throat plate.

27. In a machine of the class specified, the combination with sewing machine instrumentalities consisting of a single vertically reciprocating needle provided with means for guiding a strand thereto, a work support, a vertically movable presser foot and a throat plate, of loop forming means oscillatingly mounted below the work support and throat plate, and a vertically reciprocating carrier mounted below the loop forming means and normally clear of the latter and having a knife thereon disposed at an angle of inclination and movable upwardly into a portion of the loop forming means to sever the successively formed loops.

28. In a machine of the class specified, in combination with a single vertically reciprocating needle provided with means for guiding a strand thereto, a work supporting and feeding means through which the needle operates, of loop forming mechanism disposed below the work support and con-

sisting of a fixed stop, a laterally and longitudinally movable loop retaining arm cooperating with said stop, a slotted oscillating hook device below the stop and arm, and a vertically reciprocating carrier below the oscillating hook device and having an angularly disposed knife thereon movable into the slot of the hook device for severing successive loops held by the said hook device.

29. In a machine of the class specified, the combination with a work support, work feed means and a single vertically reciprocating needle provided with means for guiding a strand thereto, of loop forming mechanism below the work support and including means for forming a loop, and a vertically reciprocating carrier below the loop forming means and having an angularly disposed reversible knife with double cutting edges to cooperate with the loop forming means for severing the successive loops as formed to produce a closely associated pile.

30. In a machine of the class specified, the combination with a single vertically reciprocating needle provided with means for guiding a strand thereto, a work supporting and feeding means through which the needle operates and a presser foot, of loop forming mechanism beneath the work support and including a fixed stop, a laterally and longitudinally movable loop retaining arm having a free end to abut against the stop and hold a portion of a loop and also shift the latter on the stop, an oscillating hook device below the stop and loop retaining arm, a vertically reciprocating carrier having a knife thereon to cooperate with the hook device for severing successive loops held by the hook device, and means for operating the arm, hook device and carrier in timed relation.

In testimony whereof I have hereunto set my hand in presence of two subscribing witnesses.

AUGUST J. CARTER.
